3 Claims. (Cl. 173—114)

This invention relates to a surface working mechanical tool for metal, stone and the like.

It has been well known that, in a surface working mechanical tool for metal, stone and the like, a pin cluster holder in which a plurality of pins are mounted is pneumatically operated so as to retire towards a piston, and the pins are projected by a dashing power of the piston intermediate a throttle anvil so that the tips of the pins act on a surface to be worked. In accordance with such prior arts, the compressed air which operates the pin cluster holder is admitted into a cylinder regardless of the operation of the piston. It is difficult therefore to operate the pin cluster holder in such a manner that the same carrying the pins is advantageously in a retired position when the piston is at the highest speed.

The principal object of this invention is to provide a surface working mechanical tool in which a pin cluster holder is advantageously in a retired position when a piston is at the highest speed.

Another object of this invention is to provide a surface working mechanical tool of the character referred to that will be of simple structure and not likely to get out of order.

Still another object of this invention is to provide a surface working mechanical tool of the class described which also blows away chips automatically.

Briefly stated in accordance with one aspect of this invention, there is provided a surface working mechanical tool for metal, stone and the like, comprising a piston adapted to reciprocate in a cylindrical member by the action of compressed air admitted into an inside cavity formed in the piston, a pin cluster holder adapted to reciprocate in an extended cylindrical member, and a throttle anvil interposed between said piston and said pin cluster holder in said extended cylindrical member. The compressed air is supplied through a main air port provided in the piston. The pin cluster holder carries a plurality of pins having heads in such a manner that the pins are axially slidably countersunk into the pin cluster holder on the rear surface thereof, respectively. The pins are projected forwards by a dashing power of the piston intermediate the throttle anvil so that the tips of the pins impulsively act on a surface of work, respectively. The surface working mechanical tool further comprises a small air port provided in the piston in front of the main air port and adapted to pass air from the inside cavity to an air outlet, a forward step provided around the pin cluster holder, and a number of flutes and second air inlets adapted to communicate the air outlet with a space in front of the step. The air outlet is adapted to be communicated with the main air port through the inside cavity and the small air port so as to admit the compressed air into the space and subsequently with the inside cavity through the main air port so as to exhaust air held inside the piston to the same space whereby the pin cluster holder carrying the pins is made to retire towards the throttle anvil.

The invention will be better understood and other objects and additional advantages of the invention will become apparent upon perusal of the following description taken in connection with the drawings, in which:

FIG. 1 is an axial sectional view of a surface working

mechanical tool embodying this invention and shows a position where the pin cluster holder is retiring while the piston is just started forwards;

FIG. 2 is a cross sectional view on line II—II of FIG. 1;

FIG. 3 is a view similar to FIG. 1, but showing an instance where the piston strikes the throttle anvil and the pin cluster holder has been retired ultimately; and

FIG. 4 is another view similar to FIG. 1, but showing a position where the pin cluster holder and pins are projected forwards so as to work by the tips of the pins while the throttle anvil has been almost stayed and the piston is being retired.

Referring more particularly to the drawings, the preferred embodiment of this invention will now be described; however, this description will be understood to be illustrative of the invention and not as limiting it to the particular construction shown and described. A cylindrical member 3 is provided inside a body 1 secured thereto. The rear end of the cylindrical member 3 is sealed by a threaded rear stopper 4 screwed therein. The front end of the cylindrical member 3 is radially expanded and axially extended into an extended cylindrical member 2 intermediate a flange 2a. The front end of the extended cylindrical member 2 is sealed by a threaded front stopper 5 having a central opening. A piston 6 is provided in the cylindrical member 3 so as to be slidable axially in the latter. The hind part of the piston 6 is somewhat expanded radially so that the peripheral surface of the hind part of the piston 6 is adapted to be slidable axially on the hind part of the inside wall of the cylindrical member 3, while the fore part of the cylindrical member 3 is somewhat narrowed radially so that the peripheral surface of the fore part of the piston 6 is adapted to be slidable axially on the fore part of the narrowed inside periphery of the cylindrical member 3. There is provided a shoulder 6a intermediate the fore part and the hind part of the piston 6. A corresponding shoulder is formed between the fore part and the hind part of the inside wall of the cylindrical member 3.

A number of air inlets 10 are provided through the hind part of the wall of the cylindrical member 3, which is communicated with an air pipe 1a provided through the body 1 so as to supply compressed air from a source (not shown) to the air inlets 10. The piston 6 has a rear-open axial cavity 11a, the interior space of which is adapted to be communicated with the air inlets 10 through the annular space between the two shoulders and a number of main air ports 11 provided radially through the fore part of the piston 6. A small air port 12 is provided radially through the piston 6 so as to communicate the inside cavity space 11a with a number of air outlets 13 provided radially through the fore part of the cylindrical member 3 when the piston 6 is rather in the hind position. However, when the piston 6 is in the fore position, the air outlets 13 is communicated with the inside cavity 11a through the main air ports 11, while the air inlet 10 is closed.

There is a throttle anvil 7 inside the extended cylindrical member 2, being adapted to be slidable axially on the inside periphery of the extended cylindrical member 2. However, it is not necessary to slide the throttle anvil 7 so far from the flange 2a. There is a pin cluster holder 9 having a radially expanded rear part and a rather narrowed fore part. The radially expanded rear part is adapted to be slidable axially on the inside periphery of the extended cylindrical member 2. The fore part of the pin cluster holder 9 is adapted to be slidable axially on the inside periphery of the central opening of the threaded front stopper 5. Thus a forward step 15 is formed between the peripheries of the radially expanded rear part and the fore part of the pin cluster holder 9. An annular space is formed between the forward step

15 and the rear end of the threaded front stopper 5. A number of flutes 14 are provided in the inside wall of the body 1 in such a manner that the rear ends of the flutes 14 are communicated with the air outlets 13 and the front ends thereof are communicated with a number of second air inlets 16 provided radially through the fore part of the extended cylindrical member 2 so as to communicate the air outlets 13 with the space in front of the step 15. There are provided a number of radial second air outlets 17 for exhausting air in the space in front of the step 15 when the pin cluster holder 9 has been retired. It is a well known structure that the air pipe 1a is communicated with the main air ports 11, while, in accordance with this invention, there is provided an annular groove in the inside wall of the body 1. The annular groove is air-tightly shielded from the air pipe 1a by a bulkhead 1b and leads to the flutes 14. The radially expanded rear part of the pin cluster holder 9 is provided with a number of axial holes. Pins 8 are countersunk at their rear expanded ends in the rear ends of the axial holes and adapted to be slidably axially in the axial holes, respectively. The front ends or tips of the pins 8 are extended through and projected beyond the central opening of the threaded front stopper 5, respectively.

In operation, the piston 6 starts its forward motion by the action of compressed air admitted from the air pipe 1a into the axial cavity 11a through the air inlets 10, the clearance between the inside periphery of the cylindrical member 3 and the outside periphery of the piston 6, and the main air ports 11, as shown in FIG. 1. At the same time, the compressed air admitted into the axial cavity 11a is further led to the flutes 14 through the small air port 12 and the air outlets 13 whence the air is passed through the second air inlets 16 to the annular space in front of the forward step 15 so as to slide the pin cluster holder 9 rearwards. It is the position that FIG. 3 shows, where the piston 6 is most accelerated. At that time, the throttle anvil 7 and the pin cluster holder 9 are in the rearmost position thereof and the throttle anvil 7 is in contact with the pin cluster holder 9 and the expanded heads of the pins 8. By virtue of the structure in accordance with this invention, it is possible to cooperate the operation of the piston 6 with the retiring motion of the pin cluster holder 9 so that the piston 6 strikes the throttle anvil 7 when the former is at the highest speed and at the same time when the pin cluster holder 9 has just come in contact with the throttle anvil 7. By virtue of the provision of the flange 2a between the cylindrical member 3 and the extended cylindrical member 2, the rearward motion of the throttle anvil 7 is restricted by the flange 2a so that the throttle anvil 7 is prevented from an excessive retirement whereby it is possible to strike it by the piston 6 at the highest speed thereof simultaneously with the contact of the throttle anvil 7 with the pin cluster holder 9. Thus the kinetic energy of the piston 6 is transmitted most effectively to the pin cluster holder 9 and the pins 8 intermediate the throttle anvil 7 without any mis-hit. The transmission of energy is rendered in the accurately required position.

When the pin cluster holder 9 has been energized as above, the throttle anvil 7 itself is deenergized so that it does not move forwards appreciably. However, when the tool is positioned front side down, it is probable that the throttle anvil 7 slides forwards by gravity. As it is necessary to retire the throttle anvil 7 to its rearmost position for the next cycle, it is preferred to provide a suitable means (not shown) for anchoring the throttle anvil 7 to the rear position. Meantime, the piston 6 is retired by the reaction as shown in FIG. 4.

The pin cluster holder 9 is made to retire to the rear position as explained hereinbefore. However, the action of the compressed air admitted into the second air inlets 16 through the small air port 12 only during the latter is communicated with the air outlets 13 is not sufficient for

retiring the pin cluster holder 9 so far as the position of in contact with the throttle anvil 7, because of the fact that the cross sectional area of the small air port 12 is far smaller than that of the main air ports 11. Under these circumstances, when the piston 6 has been advanced so as to disengage the small air port 12 from the air outlets 13, the main air ports 11 are positioned in communication with the air outlets 13 so as to exhaust air from the inside axial cavity 11a to the second air inlets 16 through the same passage as above. Even the air has been expanded within the inside axial cavity 11a, it has still substantial pressure and is voluminous so that the pin cluster holder 9 which has been retired substantially is further retired so far as the position of in contact with the throttle anvil 7 by the action of the exhausted air acting on the forward step 15. When the pin cluster holder 9 has been retired to the rearmost position, the second air outlets 17 is communicated with the space in front of the forward step 15 so as to exhaust air from the tool.

In accordance with the prior art, a passage of exhausting air which has driven the piston is provided apart from a passage for leading air for driving the pin cluster holder. By virtue of this invention, such a structure is simplified so as to be easily designed. In addition, all volume of the exhausted air is directed to the tips of pins so that the chips are blown away from the surface to be worked.

While a particular embodiment of this invention has been illustrated and described, modifications thereof will readily occur to those skilled in the art. It should be understood therefore that the invention is not limited to the particular arrangement disclosed but the appended claims are intended to cover all modifications which do not depart from the true spirit and scope of the invention.

What is claimed as new and desired to be secured by Letters Patent of the United States is:

1. A surface working mechanical tool for metal, stone and the like, comprising a piston having an inside cavity and adapted to reciprocate in a cylindrical member by the action of compressed air admitted into said cavity through at least a main air port provided in said piston, a pin cluster holder adapted to reciprocate in an extended cylindrical member, said pin cluster holder carrying a plurality of pins having expanded heads in such a manner that the pins are axially slidably countersunk into said pin cluster holder on the rear surface thereof, respectively, a throttle anvil interposed between said piston and said pin cluster holder in said extended cylindrical member, said pins being projected forwards by a dashing power of said piston intermediate said throttle anvil so that the tips of said pins impulsively act on a surface of work, respectively, a small air port provided in said piston in front of said main air port and adapted to pass air from said inside cavity to at least an air outlet, a forward step provided around said pin cluster holder, and a number of flutes and second air inlets adapted to communicate said air outlet with a space in front of said step, said air outlet being adapted to be communicated with said main air port through said inside cavity and said small air port so as to admit said compressed air into said space and subsequently with said inside cavity through said main air port so as to exhaust air held inside said piston to the same space whereby said pin cluster holder carrying said pins is made to retire towards said throttle anvil.

2. A surface working mechanical tool for metal, stone and the like comprising a body having a cylindrical member and an extended cylindrical member, a piston having an inside cavity and adapted to reciprocate in said cylindrical member by the action of compressed air admitted into said inside cavity through at least a main air port provided in said piston, a pin cluster holder adapted to reciprocate in said extended cylindrical member, said pin cluster holder carrying a plurality of pins having expanded heads in such a manner that the pins are axially slidably

countersunk into said pin cluster holder on the rear surface thereof, respectively, a throttle anvil interposed between said piston and said pin cluster holder in said extended cylindrical member, said pins being projected forwards by a dashing power of said piston intermediate said throttle anvil so that the tips of said pins impulsively act on a surface of work, respectively, and an air supplying system for driving said pin cluster holder, comprising a small air port provided in said piston in front of said main air port, at least an air outlet provided through said cylindrical member, an annular groove provided in the inside wall of said body, a number of axial flutes provided between said body and said extended cylindrical member, and a number of second air inlets provided through said extended cylindrical member, said air outlet being adapted to be communicated commonly but alternately with said main air port so as to admit said compressed air into said air outlet through said main air port, said inside cavity, and said small air port and subsequently admit exhausted air from said inside cavity into said air outlet through said main air port, and said compressed air and said exhausted air being directed from said air outlet to a frontward step provided around said pin cluster holder through said annular groove, said flutes, and said second air inlets so as to retire said pin cluster holder towards said throttle anvil.

3. In a surface working mechanical tool comprising a casing having respective front, intermediate and rear connecting bores having a common longitudinal axis, said front bore extending to the front of said casing, said intermediate bore of greater diameter than the other bores to define respective front and rear stop shoulders at the respective junctions of said intermediate bore with said front and rear bores, a piston having a hollow piston bore frictionally slidably received within said rear bore and adapted to protrude into said intermediate bore, an anvil frictionally slidably received within said intermediate bore and adapted to seat against said rear shoulder, a pin cluster holder having a hollow shank frictionally slidably received within said front bore and a head of increased diameter frictionally slidably received within said intermediate bore, said head having through longitudinal head bores communicating with the hollow shank

space, and pins slidably received within said head bores and protruding forwardly of said casing; the improvement wherein said casing has a compressed air inlet communicating with said rear bore, said piston having a main radial port extending to its bore and communicating with said casing inlet except in the forward position of said piston, said piston having an auxiliary air port extending to its bore and located forwardly of and of smaller diameter than said main air port, said casing having air passage means communicating between said rear bore intermediate said air inlet and the front of said rear bore and said intermediate bore forwardly of said head, said main port communicating with said air passage means and said auxiliary port out of communication therewith in forward piston position and vice versa in rearward piston position, said ports positioned and dimensioned relative to said casing inlet and said air passage means whereby compressed air entering said piston bore from said casing inlet through said main port forces said piston to its forward position and at the same time passes through said auxiliary port and said air passage means to drive said holder head rearwardly, said holder head thereby abutting said anvil and said piston striking said anvil, said pins being thereby driven forwardly, said piston being then adapted to exhaust air through said main port and said air passage means whereby to raise said holder head again.
